(57) **CLAIM**

The ornamental design for a wide area network (WAN) apparatus, as shown and described.

DESCRIPTION

FIG. 1 is a front perspective view of a wide area network (WAN) apparatus with moveable antennas in a first position, each of the moveable antennas in one position of a ninety degree range of motion, in accordance with some embodiments;

FIG. 2 is a back perspective view of the wide area network (WAN) apparatus of FIG. 1;

FIG. 3 is a front view of the wide area network (WAN) apparatus of FIG. 1;

FIG. 4 is a right side view of the wide area network (WAN) apparatus of FIG. 1;

FIG. 5 is a back view of the wide area network (WAN) apparatus of FIG. 1;

FIG. 6 is a left side view of the wide area network (WAN) apparatus of FIG. 1;

FIG. 7 is a bottom view of the wide area network (WAN) apparatus of FIG. 1;

FIG. 8 is a top view of the wide area network (WAN) apparatus of FIG. 1;

FIG. 9 is another front perspective view of the wide area network (WAN) apparatus of FIG. 1 showing our new design in a second position;

FIG. 10 is another top view of the wide area network (WAN) apparatus of FIG. 1 showing our new design in a third position;

FIG. 11 is another front view of the wide area network (WAN) apparatus of FIG. 1, shown in the third position;

FIG. 12 is another bottom view of the wide area network (WAN) apparatus of FIG. 1, shown in the third position;

FIG. 13 is another back view of the wide area network (WAN) apparatus of FIG. 1, shown in the third position;

FIG. 14 is another front perspective view of the wide area network (WAN) apparatus of FIG. 1 shown with environment; and,

FIG. 15. is another back perspective view of the wide area network WAN apparatus of FIG. 1 shown with environment. The broken lines immediately adjacent the shaded areas show portions of the wide area network (WAN) apparatus

(Continued)

that form no part of the claimed design while all other broken lines are directed to environment; the broken lines form no part of the claimed design.
